CLAIM

The ornamental design for a coffee lid spill stopper, as shown and described.

DESCRIPTION

FIG. 1 is a front view, showing front surface of the coffee lid spill stopper;

FIG. 2 is an end view, showing the end of the stopper which projects out of an opening in a container;

FIG. 3 is an end view, showing the end of the stopper that is inserted into an opening in a container;

FIG. 4 is a side view, showing the side of the stopper; and,

FIG. 5 is a view of the stopper in use, plugging an opening in a container.

The broken lines in the drawings depict environmental subject matter only and form no part of the claimed design.
